(57) CLAIM

The ornamental design for a receptacle plug with grip, as shown and described.

DESCRIPTION

FIG. 1 is a perspective view of a receptacle plug with grip embodying the design;

FIG. 2 is a top view of the receptacle plug with grip thereof; and,

FIG. 3 is a back view of the receptacle plug with grip thereof. Any broken lines depict unclaimed subject matter and form no part of the claimed design.

1 Claim, 3 Drawing Sheets

FIG. 1

FIG. 3
